UNITED STATES PATENT OFFICE

FREDERICK W. FRINK, OF SCHENECTADY, NEW YORK, ASSIGNOR TO GENERAL ELECTRIC COMPANY, A CORPORATION OF NEW YORK

HIGH-FREQUENCY SIGNALING SYSTEM

Application filed September 27, 1928. Serial No. 308,775.

My invention relates to high frequency signaling systems, and more particularly to carrier current communication systems employing means for repeating signals between the different stations of the system. Still more particularly my invention relates to means for repeating signals between carrier current stations each of which both transmit and receive at the same frequency, but of which certain stations operate at different frequencies from the others. The equipment at the different stations may be of the nature indicated, for example, in Patent No. 1,696,566, Emmett F. Carter, issued December 25, 1928.

In systems in which carrier current transmitted over the lines of a power distribution system are employed for communication purposes the frequency of the current employed is usually determined either by the characteristics of the line, or by the fact that independent carrier channels are desired, as when the different systems are conductively interconnected. Accordingly carrier currents for communication purposes upon different power distribution systems, or upon different lines, or branches, of the same system may necessarily be of different frequencies. Frequently it may be desirable to effect communication between stations located on such different systems, or such different lines, or branches of the same system, which stations operate at different frequencies. When such interconnection between different lines or between stations operating at different frequencies on the same line is desired different expedients may be utilized for accomplishing the purpose. Interconnecting circuits between the different lines may, of course, be utilized in such a manner that all of the lines become a common conducting channel for carrier current. If desired a repeating station of the type shown and described in application, Serial No. 262,581 of William A. Tolson, entitled Signal system, filed March 17, 1928, and which is assigned to the same assignee as the present application may be connected in the interconnecting circuit between the different lines, this station being arranged to repeat the signals received from

either line to the other line at the frequency at which the stations on the other line are adapted to operate. As another expedient means, for example, of the type shown in application, Serial No. 192,751 of Stanley A. Clark, entitled High frequency communication systems filed May 19, 1927, and which is assigned to the same assignee as the present application, may be employed whereby each station on each line may be arranged to operate at either of two frequencies.

While either of the above expedients offer satisfactory solutions to the problem situations may occur, as for example, where no housing facilities are available at the point where the interconnection of the different systems can most economically be made, or when the systems are extensive such that repeating stations are employed in one or both of the different lines for amplification purposes that means provided in accordance with my present invention may more economically be provided.

An object of my invention is to provide means which may be located at any suitable point upon either line such that signals received from any of the stations on either line may be repeated to stations on the other line at the frequency at which stations on the other line operate.

A further object of my invention is to provide means in connection with a repeating station which may be used for repeating signals between stations on the same line whereby substantially the same equipment may be utilized for repeating signals between stations on the said line and those of a separate line or between the previously mentioned stations on the same line and other stations which operate at a different frequency.

A further object of my invention is to provide means whereby intercommunication may be had between three or more stations connected to the same or to different lines, at least two of which stations, located on the same side of the repeater operate at different frequencies, and to provide means whereby this may be accomplished with a minimum of equipment at the repeating station.

While I have particularly mentioned the

repeating of signals between different lines of a power distribution system or between different systems it will, of course, be understood that I do not wish to be limited in this respect since the same may be accomplished where stations operating at different frequencies are associated with the same line.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 represents a repeating station located upon a transmission line which may be utilized for repeating signals between stations on that line and stations on a second line at a different frequency; Fig. 2 shows in greater detail the circuits which may be employed in connection with the system shown in Fig. 1, and Fig. 3 represents a repeating station which is adapted to repeat signals located in different directions from the station and between either of these stations and stations on a different line.

Referring to Fig. 1 of the drawing I have shown at 1 and 2 a pair of power distribution systems, both of which have associated therewith carrier communication stations 3 and 4. The stations 3 which are located upon the system 1 may operate at the same frequency and at a different frequency from the station, or stations, 4 located upon the system 2. The two systems 1 and 2 may be interconnected by means of a suitable coupling circuit 5 which is represented in the drawing as a pair of condensers but which may comprise any suitable means offering a low impedance to current of the carrier frequency and a high impedance to current of the power frequency. This interconnecting circuit may be located at some point where the two systems are in close proximity but where it is impractical, as for example, due to the lack of housing facilities, etc., to locate a repeating station whereby the different stations 3 and 4 may intercommunicate. In order that these stations may intercommunicate without the necessity for so arranging the circuit at each of the stations that all of the individual stations may operate at different frequencies, I have provided a repeating station 6 which may be located at any point upon either of the lines 1 or 2 and which is so arranged that it will repeat signals received from any of the stations 3 to the stations 4 and vice versa. Since station 6 is arranged to receive signals from the line 1 and to return signals to the same line for transmission in the same direction from which they were received I choose to call the repeater located at the station 6 a "reflex repeater."

The repeater at the station 6 comprises the usual balance transformer arrangement, or hybrid coil, 7 which is connected to the transmission line 1 through coupling condensers 8 and a suitable tuned circuit arrangement 9. This tuned circuit device is so constructed and arranged that it offers a low impedance to currents of the frequencies at which the stations 3 and 4 operate and a high impedance to other frequencies. The hybrid coil 7 is provided with a pair of output conductors 10 to which are connected the input circuits of a pair of detectors 11 and 12, these input circuits being connected in series. The hybrid coil 7 is also provided with an input winding 13 which is arranged to be energized with currents supplied from the output circuit of an amplifier 14. The input circuit to the detector 11 is tuned to respond to the frequency of stations 3 which are located upon the system 1 and that of the detector 12 is tuned to respond to the frequency of stations 4 which are located upon the system 2.

The amplifier 14 is arranged to be supplied with high frequency currents from either of two oscillation generators 19 and 26, the oscillation generator 19 being adjusted to produce high frequency current having the frequency to which the stations 4 are adapted to respond and the oscillation generator 26 being arranged to produce current having the frequency to which the stations 3 are adapted to respond. The operation of the oscillation generator 19 is controlled in response to voice currents received from the stations 3 through detector 11 and line amplifier 16 by means of a suitable electron discharge device 17, which is supplied with speech currents from the output circuit of the line amplifier 16. Similarly the operation of the oscillation generator 26 is controlled in response to speech frequencies received from the stations 4 through detector 12 and line amplifier 23 by means of a control electron discharge device 25 which is supplied with speech currents from the output circuit of amplifier 23.

The amplifier 14 is provided with a suitable modulating device 22 which may be of any well-known construction and which is arranged to be supplied with speech currents through amplifiers 18 and 24 from either of the detectors 11, 12.

As thus arranged the operation of the system is as follows: When currents are received having a frequency at which the stations 3 are adapted to operate they are demodulated by the detector 11 and the audio currents detected therefrom are amplified by the amplifier 16 and supplied to the control device 17 and through amplifier 18 to the modulator 22. The control device 17 causes the oscillation generator 19 to produce oscillations having the frequency of the station 4, these oscillations being amplified

5 by the device 14 and modulated by the device 22 in response to the received voice currents. These currents are then supplied to the line from which they are received by the station 4. The control device 17 at the same time causes energization of a relay 20, thereby interrupting the output circuit from the detector 12 and preventing operation of the oscillation generator 26 in response to any currents which might be produced in the 10 output circuit of the detector 12 in response to currents which may be supplied thereto, either from the amplifier 14 or from the line.

15 In the same way currents received from the station 4 are rectified by the device 12 and the audio currents detected therefrom are amplified by the line amplifier 23 and supplied to control tube 25 and speech amplifier 24. The control tube in turn causes 20 the production of oscillations by the generator 26 which are supplied to the amplifier 14, these oscillations being modulated by the device 22 and supplied to the line and to the stations 3. The operation of the control 25 device 25 similarly causes energization of the relay 27, thereby interrupting the output circuit from the detector 11.

30 The circuits by means of which the above results may be accomplished are more completely illustrated in Fig. 2 in which the electron discharge amplifier 14 is shown as having an anode circuit extending through the winding 13 and modulation reactor 28 to the cathode. The grid circuit of the amplifier 14 is arranged to be supplied with currents through coupling condensers 29 and 30 from either of a pair of oscillation 35 generators 26 and 19 respectively. These oscillation generators are of any suitable 40 construction employing electron discharge devices. The anode circuit of the electron discharge device 19 extends from the anode of that device through a source of potential 31, resistance 32, space between the cathode 45 and anode of control device 17 to the cathode of the device 19. The grid of the control device 17 is normally biased negatively by means of a source of potential 32' with respect to its cathode, such that sufficient current cannot flow in the anode circuit to permit 50 the production of oscillations by the device 19. The grid potential, however, of this device may be controlled in response to audio currents received from the detector 11 through the circuit 15, line amplifier 16 and control amplifier 32. These voice currents are rectified by the device 33, thereby causing a potential to be produced upon a 55 resistance 34, which is connected between the grid and cathode of the device 17, having a polarity opposite to that of the battery 32'. Thus when audio currents are received from the detector 11 the grid of device 17 will become sufficiently positive to permit 60 current to flow in the anode circuit of the

device 19 thereby to cause that device to produce oscillations. This current flowing through the resistance 32 will cause a positive potential to appear upon the grid of electron discharge device 35 and thereby cause operation of relay 20 and interruption 70 of the output circuit of detector 12.

75 The adjustment and operation of the devices 17, 33 and 35 are more fully described in Patents No. 1,696,566, Emmett F. Carter, entitled High frequency duplex signaling system, issued December 25, 1928; and No. 1,696,590, Lester F. Bird, entitled Signaling system issued December 25, 1928, and copending application Serial No. 262,581 of William A. Tolson, entitled Signal system, filed March 17, 1928, all of which are assigned to the same assignee as the present application.

80 Oscillations produced by the device 19 will be supplied to the amplifier through the coupling condenser 30. These currents are then amplified by device 14 and modulated by the modulating device 22 in response to currents received through the line amplifier 16 and speech amplifier 18. The output currents 90 from amplifier 14 are then supplied to the winding 13 and to the line 1.

95 The circuit arrangements for controlling the oscillation generator 26 and the relay 27 are identical with those just described in connection with the oscillation generator 19 and the relay 20 with the exception that voice currents for controlling these devices are received from the detector 12, through the line amplifier 23 and control amplifier 36. Audio 100 currents are supplied from line amplifier 23 through speech amplifier 24 to the modulator 22.

105 As thus described it will be seen that the same coupling circuit connecting the repeating station to the line, and the same high frequency amplifier and modulating device are used for repeating the signals in both directions.

110 In Fig. 3 I have shown a repeating station which is arranged to repeat signals between the stations 3 and 4 or between any of these stations and a third station 37 all of which may operate at different frequencies. The station 37 may be located upon line 1 in which case its frequency is preferably different from that of the stations 3 or it may be located upon an entirely different power system in which case its frequency may be determined in accordance with the characteristics of that system and requirements of the communication channel.

115 The repeating system shown in Fig. 3 comprises a pair of oscillation generators 38 and 39. The oscillation generator 38 is normally connected to supply currents through the armatures of relay 40, in their left-hand position, to the high frequency amplifier 41 from which they are supplied through hybrid coil 42 to the station 37. These currents will of 120

course have the frequency to which the stations 37 are adapted to respond. The oscillation generator 39 is normally connected to supply current through the amplifier 43 and hybrid coil 44 to the line 1 having the frequency to which the stations 3 are adapted to respond.

The oscillation generator 39 is provided with an inductance 45 which may be connected in a suitable manner to vary the frequency of the oscillation generator, as for example by being connected in circuit relation with the oscillatory circuit of the generator. This inductance is of such value that when so connected, as by means of a relay 46, the current produced by the oscillation generator will be of the frequency to which the station 4 is adapted to respond. The oscillation generator 38 is similarly provided with an inductance 47 which may be connected in parallel with the oscillatory circuit of the generator by means of a relay 48. When so connected the oscillation generator 38 will produce currents having the frequency to which the stations 3 are adapted to respond. The relay 40 is arranged to be energized simultaneously with the relay 48 and in operating its contacts to the right connects the output circuit of the oscillation generator 38 to the input circuit of amplifier 43 in a manner such that these currents may be supplied through that amplifier to the line 1 and to the stations 3.

For the purpose of controlling the relays 40 and 48, which are associated with the oscillation generator 38, and the relay 46, which is associated with the oscillation generator 39, and other relays later to be indicated, in response to currents received from the stations 3, 4 and 37 suitable selectors 49 and 50 are provided. The selector 49 is adapted to respond to current flowing in the anode circuit of either of the detectors 51 or 52, the detector 51 being tuned to respond to currents of the frequency produced by the stations 3 and the detector 52 being tuned to respond to currents produced by the stations 4. The selector 50 similarly responds to current flowing in the anode circuit of a detector 53 which is tuned to respond to currents produced by the station 37.

A further understanding of the system shown in Fig. 3 may best be had by reference to its operation.

As shown the system is normally connected to repeat signals between the stations 3 and the stations 37. As such its operation is as follows. When the operator at the station 37 speaks into the microphone he will cause carrier current modulated with voice currents to be supplied to the detector 53 where it will be rectified. Voice currents resulting from this rectification will be supplied through a line amplifier 54 to a control tube 55. This control tube is arranged to control the operation of the oscillation generator 39 in the

manner described in connection with Fig. 2. High frequency current having the frequency at which the station 3 is adapted to respond will then be supplied through the radio amplifier 43 and the hybrid coil 44 to the line and hence to the stations 3. This high frequency current will be modulated with voice currents supplied from the amplifier 54 through a speech amplifier 56 to modulating device 57 which is associated with the anode circuit of the amplifier 43 in the manner described in connection with Fig. 2.

In the same way when the operator at the station 3 speaks into his microphone he will cause modulated carrier current to be supplied to the detector 51 and rectified. The output from the detector 51 which is of voice frequency will be supplied through the armature and lower contacts of relay 58, and line amplifier 59 to a control tube 60. This control tube controls the operation of the oscillation generator 38 in the manner described causing it to produce oscillations which are supplied through the armatures and left-hand contacts of the relay 40 to the power amplifier 41. These high frequency currents are then amplified and modulated in response to the voice currents which are supplied thereto through amplifier 59, speech amplifier 61 and a modulator 62. This modulated high frequency current will then be supplied through the hybrid coil 42 to the stations 37.

Relay 62' is connected to respond to current flowing in the anode circuit of the oscillation generator 39 in the manner described in connection with relay 20 of Fig. 2, such that during operation of the oscillation generator 39 this relay is energized and short circuits the output from the detectors 51 and 52, thereby preventing any transmission of energy through the opposite channel and hence preventing operation of the oscillation generator 38. In the same way when the oscillation generator 38 operates the relay 63 will be energized to short circuit the channel in the opposite direction and thereby preventing operation of the oscillation generator 39.

Let us assume now that the operator at the station 4 desires to speak with the operator at the station 37. He will dial the number of the called party in the same manner in which he would call any station upon his own line but the number will be a special one such that the selector 49, in responding to the carrier impulses produced by the dialing device in the station 4, will cause a circuit 64 and relay 46 to be energized, thereby connecting the oscillation generator 39 to produce oscillations having the frequency at which the station 4 operates. The repeating of signals between the station 4 and station 37 will then be exactly as described previously in connection with the repeating of signals between station 3 and the station 37 with the exception that the detector 52 will be operative to

rectify the carrier current received from station 4 and the generator 39 will produce current having the frequency to which the station 4 responds.

6 If it be assumed that the operator at station 37 desires to call the station 4 he will dial a number to which the selector 50 will respond. This selector will then cause the energization of relay 46, causing the oscillation generator 39 to operate at the frequency of the station 4. The repeating of signals will then take place as described above.

10 If the operator at either of the stations 3, or 4, desires to speak with the operator at 15 the other station he will dial a number to which the selector 49 will respond to cause energization of relay 65. The relay 65 will then close both of its contacts causing energization of relays 46, 40, 48, 58 and 66. Energization of relay 46 will cause the oscillation generator 39 to operate at the frequency at 20 which the station 4 operates. The operation of relay 48 will cause the oscillation generator 38 to operate at the frequency to which 25 the station 3 responds. Operation of relay 40 will connect the output of oscillation generator 38 to the input circuit of amplifier 43 and disconnect this output circuit from amplifier 41. The operation of relay 66 will

30 connect the output from speech amplifier 61 to the input of modulator 57 and relay 58 will disconnect the output of detector 51 from line amplifier 59 and connect it to the input circuit of line amplifier 54.

35 As thus connected the repeating of signals between stations 3 and 4 will be as follows. When the operator at the station 3 speaks into his microphone he will cause modulated carrier currents to be impressed upon detector 51. Currents flowing in the 40 output circuit of detector 51, which are of voice frequency, will then be supplied through the armatures and upper contacts of relay 58 to the input circuit to the amplifier

45 54. The output from amplifier 54 will then be supplied as before to the control tube 55 and to the modulating device 57. The control tube 55 causes operation of the oscillation generator 39 and the production of high frequency oscillations having the frequency to 50 which the station 4 is adapted to respond, these currents being amplified by the device 43 and modulated by the device 57. These modulated currents are supplied through coil

55 44 to the line 1. Upon operation of the oscillation generator 39 the relay 62' will respond thereby short circuiting the output from detector 52 and preventing any transmission of energy through this channel such as might 60 cause operation of the oscillation generator 38.

When the operator at the station 4 responds by speaking into his microphone he 65 will cause modulated carrier current to be supplied to the detector 52. Audio currents

from the output circuit of this detector will then be amplified by the device 59 and supplied to the control tube 60, thereby causing operation of the oscillation generator 38. Output current from the oscillation generator 70 38, having the frequency to which the stations 3 are adapted to respond, will then be supplied through circuit 67 to the input of amplifier 43. Voice currents from the amplifier 59 will also be supplied through speech amplifier 61, armatures and contacts of relay 66 to the modulator 57 where they will be caused to modulate currents amplified by amplifier 43. Modulated carrier current having the frequency to which the stations 3 are 75 adapted to respond will then be supplied to the line, the signals being transmitted over the line in the same direction from which they were received. Upon operation of the oscillation generator 38, relay 63 will be energized thereby short circuiting the input to amplifier 54 and preventing any transfer of energy through this channel such as would cause operation of the oscillation generator 39.

80 While I have shown and described particular embodiments of my invention it will of course be understood that I do not wish to be limited thereto since many modifications both in the circuit arrangement and in the 85 instrumentalities employed may be made without departing from the spirit and scope of my invention as set forth in the appended claims.

90 What I claim as new and desire to secure by Letters Patent of the United States, is:

1. The combination in a carrier current communication system, with a plurality of power lines, intercommunicating carrier stations on each line, the stations on different lines operating at different frequencies, a carrier channel interconnecting said lines, and means located upon one of said lines between stations on said line for receiving signals from any of said stations with a carrier wave having predetermined frequency and repeating said signal to a station on a different line with a carrier wave having the frequency at which said last station operates whereby duplex communication may be effected between 100 stations on different lines.

105 2. In combination, a plurality of intercommunicating carrier signaling stations, each of said stations being arranged to transmit and receive on the same carrier frequency and certain of said stations operating on a carrier frequency different from that at which other of said stations operate, a line joining and extending beyond said stations, a repeating station connected to said line as 110 extended and arranged to receive calling and signaling currents from any of said stations and to transmit said calling and signaling currents over said line in the same direction from which they were received to another of 115 120 125 130

said stations with a carrier wave having the frequency at which said last mentioned station operates.

3. In combination, a plurality of intercommunicating carrier stations operating at different frequencies, a repeating station, an amplifier in said repeating station, a plurality of oscillation generators operating at different frequencies arranged to supply currents to said amplifier, each of said generators operating at the frequency of one of said stations, and means responsive to current received from any of said stations for causing a generator operating at the frequency of a different station to supply current through said amplifier to said different station, and means responsive to operation of each of said generators for preventing the supply of high frequency current to said amplifier from another generator.

4. In combination, a pair of intercommunicating high frequency signaling stations operating at different frequencies, a line joining said stations, a repeating station including an amplifier connected to the line, a pair of normally inactive oscillation generators connected to supply current to said amplifier, each generator being arranged to operate at a different frequency and at the frequency of one of said intercommunicating stations, and means responsive to current received from either station for rendering one of said generators operative thereby to supply current having the frequency of the other station through said amplifier to the line.

5. In combination, a plurality of intercommunicating carrier stations, each of said stations being arranged to transmit and receive on the same carrier frequency, and one of said stations operating at a different frequency from another of said stations, and a common repeating system arranged to repeat signals from either of said last mentioned stations to the other at the frequency at which said other station is adapted to operate and to repeat signals in both directions for duplex communication between either of said stations and a third station.

6. In combination, a plurality of power lines, a plurality of intercommunicating carrier stations on each line, the stations on one line operating at a different frequency from stations on another line, a common repeating system connected to one of said lines for repeating signals in both directions over said line for duplex communication between stations associated with said line, and between any of the last mentioned stations and a station on the other line.

7. In combination, a plurality of intercommunicating carrier stations, each of said stations being arranged to transmit and receive on the same carrier frequency, and one of said stations operating at a different frequency from another of said stations, and a common

repeating system arranged to repeat signals from either of said last mentioned stations to the other at the frequency at which said other station is adapted to operate and to repeat signals from either of said stations to a third station.

8. The combination in a carrier current communication system including a repeating station having a plurality of carrier channels extending therefrom, a pair of carrier current generators in said station, means utilizing said generators for repeating signals for two way communication between different channels and means utilizing the same generators for repeating signals for two way communication between different stations on the same channel.

9. The combination in a carrier current communication system including a repeating station having a pair of carrier channels extending therefrom, a carrier current generator normally connected to supply current to each channel, means for modulating current produced by each generator with current received from the other channel, and means responsive to current received from one channel for connecting the generator which is normally connected to supply current to the other channel to supply current to said one channel and for modulating current produced by either generator with current received from said one channel whereby repeating of signals between different channels or between different stations on one channel may be effected.

10. In combination, three or more carrier stations, each of said stations being arranged to transmit and receive on the carrier frequency and on a carrier frequency different from that at which other of said stations operate, and a common repeating station arranged to receive signals from any of said stations and to repeat the received signals to any of the other stations at the carrier frequency at which said other station operates.

11. The combination in a carrier current communication system including a repeating station having a pair of carrier channels extending therefrom, a carrier station connected to one channel and a plurality of carrier stations operating at different frequencies connected to the other channel, a pair of carrier current generators, means responsive to current received from either channel for causing one of said generators to supply current to the other channel having the frequency at which a station associated with said other channel operates, and means responsive to current received from either channel for adjusting the generator for supplying current to said first mentioned other channel to supply current of desired frequency to said other channel whereby duplex communication between a station on said one channel and either of a plurality of stations operating

at different frequencies on said first mentioned other channel may be carried on.

12. The combination in a carrier current communication system including a repeating station having a pair of carrier channels extending therefrom, a carrier station connected to one channel and a plurality of carrier stations operating at different frequencies connected to the other channel, an oscillation generator normally connected to supply carrier current to each channel having a certain frequency, means utilizing said generators for repeating signals in both directions between said channels, means responsive to impulses received from the mentioned other channel for changing the frequency of both of said oscillation generators and for connecting both generators to supply current to said other channel, and means responsive to current received from either station on said other channel for modulating current produced by one of said generators whereby duplex repeating of signals between stations on said other channel may be effected.

15
20
25 In witness whereof, I have hereunto set my hand this 13th day of September, 1928.
